IRONING MACHINE

Glenna McGiveron, Batavia, N. Y.

Application February 13, 1939, Serial No. 256,140

7 Claims. (Cl. 12—51)

This invention relates to ironing machines designed primarily for use in preparing some of the materials employed in the manufacture of shoes.

It has generally been the practice to provide the tips and/or vamps of shoes with fabric linings or backings. With mechanisms now in use, however, this has been done in a manner not altogether satisfactory because of the time required and of the difficulty in properly applying the backings to the leather or other materials of the shoes.

An object of the present invention is to provide a machine by means of which the application of backings to the tips and vamps of shoes can be speeded up and the backings applied quickly and smoothly in their proper positions.

It is a further object to provide a machine which supports the tips and/or vamps in positions where the operator can readily place the backings thereon after which the material is subjected to pressure and heat to cause adherence of the backings to the parts thereunder, rubber being used as an adhesive.

A further object is to provide a machine of this character which is compact and efficient, can be manufactured at low cost, and which will practically double the work heretofore performed by a single operator.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings:

40 Figure 1 is a front elevation of the machine.
Figure 2 is a top plan view thereof.

Figure 3 is a section on line 3—3 of Figure 2.

Figure 4 is a plan view of a portion of one of the sliding tables and showing thereon a complete shoe vamp and quarter to which the backing sheets have been applied preparatory to the application of heat and pressure.

Figure 5 is an enlarged section on line 5—5, 50 Figure 4, a portion of the ironing plate being shown in elevation prior to application to the work.

Referring to the figures by characters of reference 1 designates a supporting frame of any suitable construction on which is mounted a table

2 the front of which is shaped to define a V-shaped recess formed by forwardly diverging edges 3 extending from the center of the front of the table.

Extending backwardly from each of the edges 5 3 are parallel guides 4 which can be in the form of V-shaped rails as shown, the two tracks formed by these rails diverging rearwardly as shown.

A carrier 5 in the form of a plate is mounted on each track, this carrier preferably being 10 formed with grooves 6 into which the rails or guides 4 project. Thus the plates are guided in their back and forth movement.

Each carrier can be of any size desired and can be proportioned to hold one piece of the work 15 to be ironed or a couple of pieces. Adjacent to the back edge of each carrier there are provided stop pins 6' the lower ends of which are mounted to slide in recesses 7 in the carrier, these recesses containing springs 8 which support the upper 20 ends of the pins normally projected above the carrier. Thus when the work is placed on the carrier these pins constitute stops for limiting sliding movement of the work backwardly while being placed in position. In other words these 25 stop pins constitute abutments for the work when in their normal positions. This will be apparent by referring to Figures 4 and 5 wherein the work has been indicated generally at W. Obviously any desired number of these stop pins can be 30 used on each carrier, depending upon the nature and location of the work.

Studs 9 extend downwardly from each carrier at points adjacent to the centers of the front and back edges thereof and these studs are adapted 35 to work freely within slots 10 formed in the table 2. A groove 11 is preferably formed in the bottom of each carrier and in line with the studs and into this groove projects the upper end of a shaft 12 journaled in suitable bearings 13 in the frame 40 and provided at its lower end with a gear 14. A cam 16 is secured to this shaft 12 and works between the studs 9 so as to alternately thrust against the studs, the cam being so shaped, as indicated in Figure 2 as to successively thrust the 45 carrier backwardly and forwardly with pauses in between said movements of sufficient duration to afford the operator ample opportunity to remove work from the carrier and place new work thereon.

Gear 14 meshes with a gear 17 secured to a transverse shaft 18 journaled in frame 1 and this shaft is adapted to receive motion in any suitable manner from an electric motor 19 or other suitable operating means. In the struc- 50 55

ture shown the motor 19 transmits motion through chain and sprocket mechanism 20 to a reduction gearing indicated generally at 21 and motion is then transmitted through chain 5 and sprocket mechanism 22 from the reduction gearing to the shaft 18. It is to be understood, of course, that the shaft 18 is used for driving the shaft 12 of both cams 16. By referring to Figure 2 it will be seen that the cams are oppositely disposed so that when one carrier is moving forwardly the other carrier 5 is moving rearwardly.

Extending upwardly from table 2 are angular guides 23 and located adjacent to each guide is an upwardly extending pin 24 on which is mounted a spring 25. A heating and pressing head 26 is slidably mounted at its corner portions on the pins 24 and between the guides 23. Each of these heads is yieldingly supported by 20 the springs 25 and is provided, near its center, with a thrust-receiving portion 27.

Standards 28 are mounted on the table and serve to support a shelf 29 on which work can be placed. These standards have bearings 30 in which is journalled a shaft 31 and secured to the shaft above each of the thrust portions 27 is a cam 32. The two cams are extended in opposite directions as shown in Figure 1 and are adapted alternately to engage the respective 30 thrust portions 27 when shaft 31 rotates. Motion is transmitted to shaft 31 in any suitable manner, as by means of chain and sprocket mechanism 33 extending from shaft 18.

Each of the heating and pressing heads is 35 provided with suitable heating means. This heating means can be in the form of electric heating elements 34 contained therein and where such elements are used, pilot lights can be employed to indicate when they have reached the proper temperature. Switches 36 can be used 40 for controlling the heating units.

The cams 32 are arranged to operate in properly timed relation to the cams 16 so that each of the heads 26 will be pressed downwardly at 45 the beginning of the pause following the positioning of the carrier under said head and will be released immediately preceding the termination of said pause. Obviously as soon as each head 26 is released, the compressed spring 25 thereunder will raise the head out of contact 50 with the work W on the carrier thereunder.

When it is desired to use the machine the operator takes a position in front of the center of the table so that by turning slightly to the right or to the left one or the other of the carriers can be readily reached for the purpose of 55 placing work thereon or removing work therefrom. When the machine is set in motion one of the carriers is thrust forwardly while the other is thrust rearwardly and when these carriers reach the limit of their movement, they remain stationary for a sufficiently long period to enable the operator to place the work thereon or remove it therefrom. When a carrier reaches 60 its forward position, the operator places thereon the materials to be pressed and heated. In the structure shown the work comprises a whole shoe vamp and quarters indicated at S and backing pieces B formed of fabric rubber-coated on 65 the underside, the coating constituting an adhesive. The parts are positioned so as to be supported smoothly on the carrier and it will be noted that the pins 6' prevent these parts from being pushed backwardly too far thereon. As 70 soon as the work has been placed on the carrier 75

the operator turns so as to be in position to remove work from the other carrier. Following the predetermined pause in movement, the carrier on which work had been placed is thrust rearwardly into position under its heating and 5 pressing heads and as it reaches said position, said heating and pressing head is thrust downwardly against the action of the springs 25 so as to press firmly on the work and subject it to heat as well as pressure. At this time there is 10 a pause in the movement of the carrier and during this pause the other carrier is located at the front of the table where the work can be removed and new work placed thereon. Immediately prior to the termination of the pause, the 15 depressed head 26 is released so as to lift away from the work and thereafter the carriers begin their movement so that the pressed work is brought forwardly by one carrier and a new supply of work is moved rearwardly by its carrier into position below the heating and pressing head provided therefor. The operation already 20 described is then repeated.

Attention is called to the fact that every time a head 26 is lowered, it pushes downwardly on 25 the pins 6' so as to lower them. Consequently these pins offer no resistance to the pressing and heating operation.

It has been found that a machine of this type 30 will greatly increase the output of tips, vamps and quarters lined with affixed pieces and the work produced has been found free from imperfections because the operator has ample time in which to properly place the work upon the carriers and the heads 26 act efficiently to press 35 and to heat the work.

The pieces prepared for placement on the carriers can be supported on shelf 29 until they are to be used. This shelf is at all times in convenient reach of the operator.

While it is preferred to form the machine with 40 two complete units, as shown, it is to be understood that smaller machines could be made with one unit including the one carrier and one head or, in larger machines, more than two units 45 could be used, all extending radially from the operator.

While the machine is designed primarily for 50 heating and pressing parts of shoes, it is to be understood that it can be employed in the production of other articles requiring the application of two or more layers of material under heat and pressure.

What is claimed is:

1. A machine of the class described including a carrier mounted for back and forth reciprocation, a yieldingly supported heating and pressing head, means for reciprocating the carrier, said means providing pauses in the operation when the carrier reaches each limit of its movement, and 55 means for lowering the head to compress work on the carrier during one pause in the movement of said carrier.

2. A machine of the class described including a heating and pressing head yieldingly supported, 60 a carrier, means for moving the carrier into and out of position beneath the head, said means providing a pause of pronounced duration between the movements of the carrier, and means for forcing the head downwardly, maintaining it 65 in lowered position, and releasing it for upward movement during one of said pauses.

3. A machine of the class described including a heating and pressing head, guides therefor, yielding means for supporting the head, a car- 70

rier, said carrier constituting means for supporting work to be pressed and heated, means beneath the carrier for moving it into and out of position beneath the head, said means providing pauses of pronounced duration between each of the movements of the carrier, and means for lowering the head, holding it in lowered position, and releasing it for upward movement during one of said pauses while the carrier is in position thereunder.

5 4. A machine of the class described including a table, guiding means extending thereabove, a combined heating and pressing head mounted for up and down movement along said guiding means, a carrier mounted for sliding movement on the table and proportioned to support work to be pressed and heated, means beneath the carrier for moving it into and out of position beneath the head, said means providing pronounced 10 pauses between the movements of the carrier, and means operating during a pause in the movement of the carrier while positioned beneath the head, for lowering the head, holding it in lowered position, and lifting the head.

15 5. A machine of the class described including a table, guiding means extending thereabove, a combined heating and pressing head mounted for up and down movement along said guiding means, a carrier mounted for sliding movement 20 on the table and proportioned to support work to be pressed and heated, means beneath the carrier for moving it into and out of position beneath the head, said means providing pronounced 25 pauses between the movements of the carrier, and means operating during a pause in the movement 30 of the carrier while positioned beneath the head,

for lowering the head, holding it in lowered position, and lifting the head, said means including a cam mounted for rotation, and means on the head for engagement by the cam.

6. A machine of the class described including a table, a carrier mounted for reciprocation thereon and proportioned to support work to be pressed and heated, a cam beneath the carrier, means on the carrier for engagement by the cam for effecting back and forth movement of the 10 carrier and providing pronounced pauses between said movements, a heating and pressing head mounted for up and down movement above the path of the carrier, means for guiding the head, a yielding support for the head, a cam positioned 15 to depress the head, and means for operating the cams simultaneously said cams being timed to lower the head, hold it in lowered position, and release it during one of the pauses in the movement of the carrier while said carrier is positioned 20 beneath the head.

7. A machine of the class described including a table, a carrier mounted for back and forth movement thereon, resiliently supported stop means on the carrier, a combined heating and 25 pressing head above the path of the carrier, means for moving the carrier backwardly into position under the head and forwardly away from the head, said means providing pronounced 30 pauses between the movements of the carrier, yielding supporting means for the head, and means for lowering the head, maintaining it in lowered position, and releasing the head during each pause of the carrier while positioned under 35 the head.

GLENNNA McGIVERON.
